(57) **CLAIM**

The ornamental design for a body board with integral hand grips, as shown and described.

DESCRIPTION

FIG. 1 is a perspective view of a body board;

FIG. 2 is a top plan view of the body board;

FIG. 3 is a bottom plan view of the body board;

FIG. 4 is a side elevation view of one side of the body board;

FIG. 5 is a side elevation view of the other side of the body board;

FIG. 6 is a front elevation of the body board; and,

FIG. 7 is a rear elevation view of the body board.

The details shown in broken lines are for illustrative purposes only and form no part of the claimed design.
